Dec. 1800

Samuel H. Ransom, of Albany, N.Y.
Letters Patent No. 1800-Dated July 7th 1863.

The schedule referred to in these Letters Patent and making part of the same:

To whom it may concern:

Be it known that I, Samuel H. Ransom, of the City and County of Albany, and State of New York, have produced a new and original design for the plates of a Cook Stove, which stove is named the "Pathfinder"; and I declare that the annexed delineations are full and accurate representations of the ornamental design on the different plates; those plates not shown are of same design as those annexed.

A represents the oven back or front:

B " the oven end, with door in:

C " the front of stove, without doors:

D " part of the side of stove, with door:

E " one of the front doors.

These with other plates, similarly ornamented, when mounted together forming the Cook Stove called the "Pathfinder."

What I claim as my production, and desire to secure by Letters Patent, is the combination and arrangement of ornamental figures and forms represented in the accompanying photographs, forming together the ornamental design for a cook stove.
